UNITED STATES PATENT OFFICE.

HELMUTH FABIAN, OF NEW YORK, N. Y.

DOOR-HANGER.

No. 918,985.

Specification of Letters Patent.

Patented April 20, 1909.

Application filed October 22, 1908. Serial No. 459,077.

To all whom it may concern:

Be it known that I, HELMUTH FABIAN, a citizen of the United States, and a resident of the city of New York, borough of Brooklyn, in the county of Kings and State of New York, have invented a new and Improved Door-Hanger, of which the following is a full, clear, and exact description.

This invention relates to hangers for doors, windows or the like, and more particularly to a device of this class which comprises a hollow track, a carrier for supporting the door or other movable object, a retainer having a limited movement longitudinally of the carrier and embracing both sides of a flange of the carrier, and rollers or other anti-friction devices positioned by the retainer, at opposite sides of the flange and movably engaging at the inside of the track.

An object of the invention is to provide a simple, inexpensive and efficient hanger for doors, sliding windows or similar objects, by means of which the door or window is supported so that it can be opened or closed with little friction, and requires but a slight expenditure of effort to operate it, and in which the hanger occupies comparatively little space.

A further object of the invention is to provide a door hanger in which the door carrier is movably arranged within a hollow track, anti-friction devices being provided between the carrier and the track at the inner side of the latter, so that the door can move longitudinally of the track with little friction and is held against upward or downward displacement, the anti-friction devices serving to position the door against such displacement.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a front elevation of an embodiment of my invention showing the same supporting a sliding door; Fig. 2 is an enlarged longitudinal section of the track showing the carrier mounted therein; Fig. 3 is an enlarged horizontal longitudinal section of the track showing the carrier in inverted

plan view; Fig. 4 is a plan view of the retainer for positioning the rollers or other anti-friction devices; Fig. 5 is an enlarged transverse section on the line 5—5 of Fig. 2; Fig. 6 is an end view of the track and the carrier; and Fig. 7 is a transverse section showing a track and carrier of modified form.

Before proceeding to a more detailed explanation of my invention, it should be clearly understood that while the same is particularly useful as a hanger for sliding doors, for example, in elevators and the like, it can also be advantageously applied to other like purposes. By the provision of a hollow track with the door carrier movable partly within and longitudinally of the track, the anti-friction devices can be substantially inclosed, and are thus protected to a large extent against excessive wear, injury, or the accumulation of dirt, grit or the like thereon.

I provide a carrier which is T-shaped in cross section; that is, it has lateral flanges adapted to be movably seated within the track. The rollers are positioned at opposite sides of the flange and consequently engage at opposite sides of the track, thereby holding the carrier against movement or displacement up and down with respect to the track. The retainer itself holds the carrier against horizontal movement in any direction other than that of the length of the track. The retainer limits the movement of the carrier, having itself a limited movement upon the carrier. I prefer to employ ball bearings for the anti-friction devices, but of course do not limit myself to these or other details of construction of the device. These various details of construction can be altered without departing from the underlying spirit of the invention. In the accompanying drawings I have shown for example, a track which is of angular cross section. In Fig. 7 a modified form is depicted in which the track is of circular or curved cross section. It will be understood that the cross sectional form of the track can be varied to suit individual preference or special conditions.

Referring more particularly to the drawings, I provide a track 10, which is of substantially rectangular cross-section, and in the lower wall has a longitudinal slot 11, extending the entire length of the track. The door carrier 12 which at the upper part has a transverse flange 13 extended laterally in opposite directions, is movably mounted within

the track and has the body 14 projecting through the slot 11 of the track. The door 15 or other object to be supported can be secured to the carrier in any convenient manner, for example, by means of screws 16 or the like passing through suitable openings 17 in the body 14 of the carrier. At the ends, the track has caps 18 which close the track and have cross-shaped openings 19 therethrough. The caps are held in place by means of screws 20, or in any other convenient manner. The openings 19 of the caps permit the carrier 12 to be moved out of the track at the ends thereof, as is shown most clearly in Fig. 1. The carrier, at the extremities, has upwardly extending projections or pins 21 constituting stops. The openings 19 are so formed that they permit the stops 21 to pass therethrough without difficulty. The track can be mounted in place in any suitable manner, for example, by means of bolts 22 extending upwardly from the caps and having the heads countersunk therein. The bolts 22 are secured to the brackets 23 which are adapted to be secured to the door frame, or other fixed support.

A retainer 24 is movably mounted upon the carrier and consists of an elongated body 30 having at opposite sides near the middle, downwardly and inwardly disposed flanges 25 which engage at the edges underneath the flange 13 of the carrier, the retainer being seated on the upper face thereof. Between the flanges 25 and the ends of the retainer are pairs of sockets 26 diagonally disposed with respect to the retainer and formed to receive anti-friction devices 27 consisting preferably of bearing balls. The sockets are 40 downwardly tapered or otherwise suitably fashioned to hold said balls loosely. At the ends, the retainer is provided with downwardly extending sides 28 having inwardly disposed and separated wings 29. The wings are formed to receive therebetween and to position bearing balls or rollers 30, between the retainer sides and the body 14 of the carrier. It will be understood that the retainer thus positions the rollers above 50 and below the flange of the carrier, the rollers being thus adapted to engage at opposite side, that is, at the top and the bottom of the track, as is shown most clearly in Fig. 5. The lower rollers 30 movably support the carrier, while the upper rollers permit a moving engagement between the carrier and the top of the track so that the carrier and its door cannot be lifted accidentally, and thus cause an irregular movement.

60 In the modified form shown in Fig. 7, the track 31 is of circular or curved cross section, the remaining parts being suitably formed where necessary, to accommodate themselves to this shape of the track. The retainer 32, for example, has the sides 33

curved and the caps 34 at the ends of the tracks are likewise rounded.

The retainer is movable longitudinally of the track and its movement is limited by the stops 21 upon the carrier. These stops at 70 the same time serve to limit the movement of the carrier out of the track, and thus limit the movement of the door. The length of the track equals the width of the door openings and consequently the width of the door, 75 and hence is positioned half over the door opening and half at one side. When the door is closed as is shown in Fig. 1, it is projected substantially half its width from one end of the track. To open the door it is 80 moved along the track until it projects substantially half its width beyond the opposite end of the track as is indicated in dotted outline in Fig. 1. When the carrier is at one end of its travel, the retainer engages at the inner 85 side of the corresponding cap and at the stop on the carrier, thereby limiting the projection of the carrier from the track. When the door is in its opposite position, the retainer engages the cap and is engaged in 90 turn by said stop which was previously outside the track, with the projecting portion of the door.

Having thus described my invention, I claim as new, and desire to secure by Letters 95 Patent:

1. A door-hanger, comprising a track having spaced upper and lower parts, a carrier for supporting a door and having a flange between said upper and lower parts, a retainer movably mounted upon said carrier and adapted to engage at the ends of said track to limit the movement thereof, said carrier having stops limiting the movement of said retainer longitudinally of said carrier, 100 and rollers engaging between said flange and said upper and lower parts respectively, of said track, said rollers being positioned by said retainer.

2. A door hanger comprising a hollow 110 track, a carrier having a flange within said track, a retainer having a limited movement longitudinally of said track, and rollers positioned at opposite sides of said flange and engaging said track, said rollers being held 115 in place by said retainer.

3. A door hanger comprising a hollow track, a carrier having a flange within said track, a retainer having a limited movement longitudinally of said track and adapted to 120 engage the ends of said track to limit the movement of said carrier, rollers positioned above and below said flange and engaging at the inside of said track, and means on said retainer for movably positioning said rollers. 125

4. A door hanger comprising a hollow track, a carrier having a flange within said track, a retainer movable on said carrier, said carrier having stops for limiting the movement of said retainer, caps at the ends 130

of said track and having openings to permit said carrier to move therethrough, said openings permitting the movement therethrough of said stops but preventing said 5 retainer from leaving said track, and rollers positioned at opposite sides of said flange by said retainer.

5. A door hanger comprising a hollow track, a carrier T-shaped in cross section and 10 having its flange movable within said track, a retainer movable upon said carrier, stops upon said carrier for engaging said retainer, said retainer having sockets above said flange, means for preventing said retainer 15 from moving out of said track, said retainer carrying rollers under said flange, and rollers in said sockets.

6. A door hanger comprising a hollow track, a carrier movable within said track 20 and having at the upper part a transverse laterally extending flange, a retainer movable upon said flange and having flanges engaging at the under side of said flange, said retainer having sockets at the upper side of 25 said flange, rollers in said sockets, said retainer having downwardly and inwardly disposed sides each having spaced wings, a roller between said wings of each of said sides under said flange, stops on said carrier 30 for limiting the movement of said retainer, and means at the ends of said track permitting the movement out of said track of said

carrier, and preventing the movement out of said track of said retainer.

7. A door hanger comprising a hollow track having a longitudinal slot in the lower wall thereof, a carrier extending through said slot into said track and having at the upper part a transverse laterally extending flange, said carrier being movable within 35 said track, a retainer movable upon said flange and having downwardly and inwardly disposed flanges engaging at the under side of said flange of said carrier, said retainer having sockets at the upper side of said 40 flange, rollers in said sockets, said retainer having downwardly disposed sides embracing said flange and each having outwardly disposed spaced wings, a roller in said wings of each of said sides and engaging at the 45 under side of said flange, stops on said carrier for limiting the movement of said retainer, removable caps at the ends of said track and having openings therethrough, permitting the movement out of said track 50 of said carrier, and preventing the movement out of said track of said retainer.

In testimony whereof I have signed my name to this specification in the presence of two subscribing witnesses.

HELMUTH FABIAN.
